UNITED STATES PATENT OFFICE.

LOUIS H. PERLMAN, OF NEW YORK, N. Y., ASSIGNOR TO GENERAL MOTORS CORPORATION, A CORPORATION OF DELAWARE.

WHEEL.

1,388,197.

Specification of Letters Patent. Patented Aug. 23, 1921.

Original application filed June 24, 1916, Serial No. 105,693. Divided and this application filed November 8, 1919. Serial No. 336,596.

To all whom it may concern:

Be it known that I, LOUIS H. PERLMAN, a citizen of the United States, residing at New York, in the county of New York and State of New York, have invented certain new and useful Improvements in Wheels; and I do hereby declare the following to be a full, clear, and exact description of the invention, such as will enable others skilled 10 in the art to which it appertains to make and use the same.

This invention relates to improvements in wheel structures and more particularly to the locking means for demountable rims. 15 The primary object in view is the improvement in the anchoring means for the rim locking device of the general character seen specifically in my prior patent, No. 1,052,270.

With this and further objects in view, as will in part hereinafter become apparent and in part be stated, the invention comprises certain novel constructions, combinations and arrangements of parts as subsequently specified and claimed.

In the accompanying drawing:—

Figure 1 is a sectional elevation of a fragment of a wheel embodying the features of the present invention.

Fig. 2 is a fragmentary, plan view of the part seen in Fig. 1, the demountable rim being omitted.

Fig. 3 is a similar view thereof with the sleeve and parts carried thereby removed.

Fig. 4 is a view similar to Fig. 1 of another embodiment of the invention, the demountable rim being omitted and parts of the felly being broken away.

Fig. 5 is a view similar to Fig. 2 of the parts seen in Fig. 4.

Fig. 6 is a fragmentary, inverted plan of a section of the demountable rim showing the lock-receiving cap.

Referring to the drawing by numerals, 45 1 indicates the wood felly of a wheel such as the usual automobile wheel, on which felly is shrunk the felly band or fixed rim 2, having at its inner edge the supporting stop flange 3. At appropriately spaced intervals about the wheel body are arranged locking devices for tensioning the demountable rim 4 in position, the said locking devices being adapted to press the rim radially

outward away from the wheel body and at the same time, thrust it over into supporting contact with the flange 3, this result being accomplished by the exercise of an inclined pressure against the inclined wall of the rim 4. This inclined wall is preferably supplied by the provision of a cap 5 for each 50 locking device. This cap 5 is seen in section in Fig. 1, and in plan in Fig. 6, and has a substantially cylindrical exterior body threaded through the rim 4 and terminating at its inner end in a laterally-extending 55 flange 19 having preferably polysided edges as seen in Fig. 6 for facilitating engagement by an operating tool. The flange 19 serves as a stop against the inner face of rim 4 when the cap 5 is threaded home through the 60 rim. The cap 5 is formed with an internal tapering recess 18 positioned and adapted for receiving the tapered end 6 of the bolt 7, the cap being so located with respect to the axis of the bolt that the inclined face 65 of taper 6 strikes the inner part of the inclined wall formed by the recess 18 so that radial outward movement of bolt 7 effects a wedging action thrusting the rim 4 axially against the flange 3, the pressure on the rim 70 4 exerted by the bolt 7 being inclined and tending both to push the rim 4 radially away from the wheel and laterally into supporting contact with the supporting stop flange 3.

Each of the said locking devices consists essentially of a wedge 6, which, for convenience, assumes the form of a tapered tip of a bolt 7, the bolt serving as the actuator and anchoring means for the wedge. Each bolt 75 7 is threaded radially through the felly 1 and fixed rim 2 and as has heretofore been practised by me, the bolt is preferably stabilized in its anchorage by means of the use of a sleeve such as is indicated at 8, the 80 sleeve being internally threaded so as to receive the external threads of the bolt 7. The sleeve 8, as heretofore constructed by me, has been provided with various means for preventing rotation so as to prevent the 85 loosening up of the parts. The devices and methods heretofore employed while very efficient and usually relatively inexpensive have been found by me not to be the easiest to construct as a matter of manufacture. 90 The present invention, therefore, has been

devised to assure the maximum ease and cheapness of construction, while at the same time maintaining maximum efficiency.

In securing these results, I provide the outer end of each sleeve 8 with an annular flange or head 9, which is set eccentric to the sleeve 8 as clearly seen in Fig. 2. The eccentricity of the circular head 9 with respect to the sleeve 8, for each sleeve is cylindrical, insures that the sleeve cannot revolve so long as the head 9 snugly fits the surrounding elements. To this end, the rim 2 is formed with a circular opening 10 eccentrically arranged with respect to the bore 11 in the felly 1 which receives the sleeve 8. The material of the fixed rim 2 about the edge of the opening 10 is beveled as at 12, and the edge of the circular head 9 is oppositely beveled as at 13 to fit the bevel 12 so that the circular head 9 may lie flush with the outer face of the fixed rim 2, while actually overlying certain portions of the material of that rim, whereby when the sleeve 8 is clamped in engagement with the rim by means of a nut 14 threaded on to the inner end of the sleeve and acting against the inner face of the felly 1, the sleeve will be firmly clamped in such engagement with the wheel as will evenly and effectively distribute load stresses to and from the wheel body without undue strain on any part independent of other parts. A washer 15 of the lock type or any other appropriate type is interposed between the nut 14 and the inner face of the felly 1 to prevent the backing off of the nut. The bolt 7 is merely threaded through the sleeve 8 and when in its operative position is locked by a locking nut 16 threaded on to the inner portion of the bolt 40 and into engagement with the inner end of sleeve 8.

It is believed that the operation will be perfectly obvious, residing, so far as the present invention is concerned, in the retention of the sleeve 8 against accidental or other objectionable revolving in use.

When the parts are assembled as seen in Fig. 4, to remove the demountable rim 4, it is only necessary to back off the bolt 7 in each instance for withdrawing the wedge 6 from engagement with the inclined recess of the cap 5, and then to withdraw the rim 4 axially. This may be done manually and the rim may be restored by a converse axial movement and when it is approximately in position, the several bolts 7 are threaded outward for causing the wedges 6 to enter the recesses of caps 5 and to engage the inclined faces thereof at the inner portion of the recesses for exerting an inclined pressure on the rim and thus thrusting the rim axially against its seat on flange 3 and outward away from the wheel for tensioning it in position for operation. The nuts 16 of bolts 65 7, of course, are not tightened until the

bolts have assumed their final operative position.

It is obvious that the circular form of the bore 11 incident to the cylindrical form of sleeve 8, enables the bore 11 to be formed by any ordinary boring tool and does not require special fitting for such sleeves as are made other than cylindrical to prevent rotation. The advantage of forming the opening 10 is somewhat similar, being incident to the method of stamping.

In Figs. 4 and 5 are seen structures identical with those above described except that the head 9' is not arranged eccentric to the bore of the sleeve 8, but in lieu thereof has portions cut away leaving straight portions 17, 17, and with this form of construction the recess in the felly band 2 must be correspondingly formed. The other parts of the structure seen in Figs. 4 and 5 are identical with those above described, and the same reference numerals have accordingly been applied.

This application is a division of my co-pending application Serial No. 105,693, filed June 24, 1916, the latter application being a continuation of the then co-pending application Serial No. 701,214, filed June 3, 1912, so far as the disclosures agree.

What I claim is:

1. The combination, with a wheel body and a demountable rim therefor, of an internally threaded sleeve extending through a portion of the wheel body, and having means of engagement therewith, resisting inward travel of the sleeve, and a nut threaded on to the inner portion of the sleeve, and contacting with a portion of the wheel body for preventing outward travel of the sleeve, a bolt threaded into the sleeve and extending in position to engage and sustain the demountable rim on the wheel body, and a nut threaded on the inner portion of the bolt, and disposed to be threaded into contact with the first-mentioned nut.

2. The combination, with the felly and fixed rim of a wheel body, of a demountable rim-lock-receiving cylindrical sleeve extending through the felly and fixed rim and having a head eccentric to the sleeve and disposed to be surrounded by the material of the fixed rim, the edge of the head being beveled and the material of the fixed rim being correspondingly beveled for enabling the outer face of said head to lie flush with the outer face of the fixed rim while material of the head overlies material of the rim, and means for preventing outward movement of the sleeve.

3. The combination with a demountable rim, of a cap threaded into the material of the rim from the inner face of the rim outward, the cap being formed with an inwardly-opening lock-receiving recess.

4. The combination with a demountable

In testimony whereof I affix my signature
in presence of two witnesses.

LOUIS H. PERLMAN.

- rim, of a cap threaded into engagement with
the rim and having a flange adapted to en-
gage the inner face of the rim, said flange
being adapted to receive an operating tool,
5 the cap being formed with a recess designed
to receive the lock-receiving element of a
wheel body.
